UNITED STATES PATENT OFFICE.

THOMAS ISAAC SUMMERS, OF HAMILTON, ONTARIO, CANADA.

COMBINATION LOCK.

Application filed October 11, 1922. Serial No. 593,781.

To all whom it may concern:

Be it known that I, THOMAS ISAAC SUMMERS, a subject of the King of Great Britain, and a resident of the city of Hamilton, in the county of Wentworth, Province of Ontario, Dominion of Canada, have invented certain new and useful Improvements in Combination Locks, of which the following is the specification.

10 My invention relates to improvements in combination locks and the object of the invention is to provide a compact and inexpensive lock of this type which may be used for a great variety of purposes among which is 15 that of application to an automobile switch.

My invention consists essentially of a lock comprising a frame having a spindle slidably and rotatably mounted therein, a disk assembly carried by said spindle, and locking elements associated with the spindle and disks whereby the spindle may be locked against sliding movement or rotational movement at different points of its stroke as desired, all as hereinafter more particularly described and illustrated in the accompanying drawings in which:

Fig. 1 is a plan view of my invention showing the spindle at the outer end of its stroke or in what might be termed the locked position.

Fig. 2 is a view taken similar to Fig. 1 showing the spindle at the inner end of its stroke or in what might be termed the unlocked position.

35 Fig. 3 is a front view of my invention.

Fig. 4 is a longitudinal section on the line 4, 4 of Figure 2 looking in the direction of the arrows.

40 Fig. 5 is a transverse section on the line 5, 5 of Fig. 2, looking in the direction of the arrows.

Fig. 6 is a transverse section on the line 6, 6 of Fig. 2, looking in the direction of the arrows.

45 Fig. 7 is a face view of the middle disk shown in Figs. 1, 2 and 4 showing it in relation to a locking bar used in my invention.

In the drawings like characters of reference indicate corresponding parts in the 50 different views.

1 is the frame of my lock which in the form illustrated comprises the base plate 2 upon which is secured, by rivets 3, upright cross plates 4, 5 and 6.

The central cross plate 5 divides the frame 55 into a front compartment 7 and a rear compartment 8.

9 is a suitable face plate to which a dial 10 is secured by rivets 11.

The dial 10 and face plate 9 are provided with registering orifices, and 12 is an indicator disk carrying a sleeve 13 which freely extends through the aforesaid registering orifices in the dial and face plate and also engages the bottom of a slot 14 formed in the front frame member 6, so that the disk 12 is rotatably mounted with respect to the casing 1.

15 is a collar secured to the inner end of the sleeve 13.

The middle frame member 5 is provided with an orifice 16 opposite to the orifices in the face plate 9 and dial 10, the purpose of which will presently appear.

A portion of the middle frame member 75 5 is notched at 17 on the upper side of the orifice 16 also for a purpose as will appear.

18 is a spindle extending through the sleeve 13 and orifice 16 and carries at its outer end the knurled head 20.

The spindle 18 is provided with a longitudinal keyway 19 extending inwardly from the knurled head 20.

21 is a pin extending through the collar 15, sleeve 13 and freely fits into the keyway 19.

In this way while the spindle 18 is free to slide within the sleeved disk 12, said disk will be rotated simultaneously with the spindle.

22 is a disk fixedly carried by the spindle 18 and 23 and 24 are rear and front disks 90 each rotatably mounted on the spindle.

The assembly of disks 22, 23 and 24 is locked against longitudinal movement on the spindle by means of pins 25 and 26 which pass through the spindle.

The disk 22 is of smaller diameter than the disks 23 and 24.

The disk 22 is provided with a pin 27 on each side thereof and disposed diametrically opposite each other.

28 are two pins carried by the rear face of the front disk 24, and 29 are similar pins carried by the front face of the rear disk 23.

Each of the disks 23 and 24 is provided with a peripheral notch 45. The disk 22 105 is also provided with a peripheral notch 46 this notch being wider than the notches 45.

30 is a locking bar rigidly secured between

the frame members 5 and 6 and disposed parallel with and at the same height as the spindle 18.

5 The front portion of this locking bar is notched at 31 for a purpose as will presently appear.

32 is a spring plate the front end of which is supported upon pins 33 and the rear end upon pins 34.

10 This spring plate slopes downwardly towards the rear and has frictional contact with the peripheral edges of disks 23 and 24.

35 and 36 are spaced pins carried near the inner end of the spindle 13 the purpose of 15 which will appear hereinafter.

37 is the inner end of the spindle 18.

38 and 39 are the two portions of a switch which are connected to the binding posts 40 and 41 carried upon a strip of insulation 42.

20 43 and 44 are electric wires secured to the binding posts 40 and 41 respectively.

The construction and operation of my invention is as follows.

In the locked position illustrated in Fig. 1 25 it will be evident that sliding of the spindle 18 is prevented by the engagement of the rear face of the disk 23 with the end of the notch 31 in the bar 30, and also by the engagement between the pin 35 and the front 30 face of the middle frame member 5, so that the spindle is locked absolutely against sliding but is free to be rotated.

It will also be noted that as the spindle is rotated by means of the knurled head 20, 35 the indicator disk 12 and also the middle disk 22, which is fixed to the spindle, are also rotated.

40 It will also be seen that the frictional engagement between the spring plate 32 and the peripheral edges of the disks 23 and 24 will prevent these disks from being normally rotated with the spindle.

The operation of opening is as follows.

45 The spindle is rotated and the pin 27 on the front side of the disk 22 engages one of the pins 28 on the front disk 24 thus causing rotation of this disk 24, such rotation being continued until the notch 45 in this disk is in alignment with the locking 50 bar 30.

The spindle is then rotated in the reverse direction and the pin 27 on the rear face of the disk 22 engages one of the pins 29 on the rear disk 23 rotation being continued until 55 the notch 45 in this rear disk is also in alignment with the locking bar 30.

60 The direction of rotation of the spindle is again reversed until the position is reached in which the notch 46 in the disk 22 is also in alignment with the locking bar and with the notches 45.

65 In this way the notches in the three disks are brought into alignment with each other and with the locking bar.

65 The spindle may then be pushed inwardly

into its unlocked position in which operation the locking bar passes through the aligned notches in the disks.

In this unlocked position rotation of the spindle and disks is prevented by the engagement of the locking bar within the aligned orifices.

70 The spindle may now be secured in this inner unlocked position by giving it a slight turn so that the pin 36 is moved out of alignment with the notch 17 and therefore engages against the rear side of the central frame member 5 (see Fig. 6).

75 This slight turning movement of the spindle is permitted by making the notch 46 in the middle disk 22 of greater width than the thickness of the locking bar 30.

80 The notches 45 in the disks 23 and 24 are just sufficiently wider than the thickness of this locking bar to permit engagement 85 therein.

85 In the locked position illustrated in Fig. 1 it will be noted that the pin 35 prevents, by engagement with the front face of the central frame member 5, any accidental 90 sliding movement of the spindle.

If it were not for this pin, in the event of the rear disk 23 being in such a position that the notch 45 was in alignment with the locking bar, a slight sliding movement of 95 the spindle rearwardly would be possible.

The dial 10 bears any suitable graduations and the indicator disk 12 bears a line 47 to be read in conjunction with the dial markings in order to provide for the proper reading 100 of the combination.

The operation of the lock in conjunction with the switch will be clearly understood from the drawings and detailed description 105 is not thought necessary.

In Fig. 1 the switch is in the open circuit position with the lock in the locked position while in Fig. 2 the switch is in the closed position with the lock in the unlocked position.

110 The engagement of the end 37 of the spindle between the switch elements 38 and 39 closes the circuit.

The advantage of this arrangement resides in the features whereby, while the owner is driving the car with the circuit closed, the lock is unlocked but when he wishes to leave the switch open, the lock is in the locked position.

115 A valuable feature of my lock when used in conjunction with an automobile switch is that when in the unlocked position in which the switch is closed, as will be the case when the owner is in the car, the lock is always in the position to be quickly and conveniently locked and the switch opened by a simple movement of the head 20.

120 This will mean that since the locking is so conveniently accomplished there will not be the same tendency to leave the switch 130.

closed as would be the case if the locking were more troublesome.

From the foregoing it will be evident that I have devised a combination lock which will be suitable for many uses.

Many modifications may be made in my invention without departing from the spirit of the invention or the scope of the claims and therefore the forms shown are to be 10 taken as illustrative only and not in a limiting sense.

For instance, while I have illustrated the lock for use in the operation of a switch it might be of course used for many different 15 purposes.

Also it is not essential that the number of disks be limited to three as illustrated but any suitable number might be used.

Also while I have shown the frame as 20 built up with the frame cross members 4, 5 and 6 being separate and riveted to the member 2 these members might all be made in one piece.

What I claim as my invention is:

25 1. A combination lock comprising a frame, a spindle slidably and rotatably mounted therein, a plurality of disks carried by the spindle, means for selectively rotating the disks when the spindle is at one extreme end 30 of its stroke, means normally preventing movement of the spindle from this end position, means co-acting with the disks whereby sliding of the spindle is permitted when the disks are rotated to a predetermined relative angular disposition to each other, and means preventing rotation of the disks when the spindle is in its opposite extreme end 35 position.

2. A combination lock comprising a frame, 40 a spindle slidably and rotatably mounted therein, a plurality of disks carried by the spindle, means for selectively rotating the disks when the spindle is at one extreme end of its stroke, means normally preventing movement of the spindle from this end position, means co-acting with the disks whereby sliding of the spindle is permitted when the disks are rotated to a predetermined relative angular disposition to each other, and 45 means preventing rotation of the disks and spindle when the spindle is at the opposite end of its stroke.

50 3. A combination lock comprising a frame, a spindle slidably and rotatably mounted therein, a plurality of disks carried by the spindle, means for selectively rotating the disks when the spindle is at one extreme end 55 of its stroke, means normally preventing movement of the spindle from this end position, means co-acting with the disks whereby sliding of the spindle is permitted when the disks are rotated to a predetermined 60 relative angular disposition to each other,

and to the spindle, means preventing rotation of the disks and spindle when the spindle is in its opposite extreme end position, and a spring co-acting with the disks for resiliently retaining the spindle in this 70 latter position.

4. A combination lock comprising a frame, a spindle slidably and rotatably mounted therein, a plurality of disks carried by the spindle, means for selectively rotating the 75 disks when the spindle is at one extreme end of its stroke, means normally preventing movement of the spindle from this end position, means co-acting with the disks whereby sliding of the spindle is permitted when the disks are rotated to a predetermined relative angular disposition to each other, means preventing rotation of the disks when the spindle is in its opposite extreme end 80 position, and stops carried by the spindle 85 and co-acting with the frame for positively locking the spindle against sliding movement at either end of its stroke as desired.

5. A combination lock comprising a frame, a spindle slidably and rotatably 90 mounted therein, a disk assembly carried by the spindle, said assembly comprising a plurality of disks some of which are fixedly carried and others rotatably carried by the spindle, means co-acting between adjacent 95 disks whereby the rotatably mounted disks may be selectively rotated when the spindle is at one extreme end of its stroke, a friction spring clutch element engaging the rotatably mounted disks, locking means co-acting with 100 the disks and normally preventing sliding of the spindle and disks from the aforesaid end position, means for releasing said locking means and permitting sliding of the spindle 105 when the disks have been rotated to a predetermined relative angular disposition to each other and to the spindle, and means for preventing rotation of the disks and spindle when the spindle is at the opposite end of its stroke.

6. A combination lock comprising a frame, a spindle slidably and rotatably mounted therein, a disk assembly carried by the spindle, said assembly comprising a plurality of disks some of which are fixedly carried and others rotatably carried by the spindle, the disks provided with peripheral notches therein, means co-acting between adjacent disks whereby the disks may be 115 selectively rotated and the peripheral notches brought into alignment, a locking bar secured in the frame and disposed parallel to the spindle, the locking bar co-acting with the disks whereby the spindle is free to rotate but normally locked against sliding 120 when at one end of its stroke, and is permitted sliding freedom when the notches in the disks are in alignment with each other and with the locking bar.

7. A combination lock comprising a frame, 130

a spindle mounted for axial sliding movement and also for rotation therein, a disk assembly carried by the spindle, said assembly comprising a plurality of disks some 5 of which are fixedly carried and others rotatably carried by the spindle, the disks provided with peripheral notches therein, means co-acting between adjacent disks whereby the disks may be selectively rotated 10 and the peripheral notches brought into alignment, a notched locking bar secured in the frame and disposed parallel to the spindle, the disks adapted to project into the notch in the locking bar when the spindle 15 is at one end of its stroke, and the locking bar adapted to project into the aligned peripheral notches in the disks as the spindle is moved axially to the opposite end of its stroke.

20. 8. A combination lock comprising a frame, a spindle slidably and rotatably mounted therein, a disk assembly carried by the spindle, said assembly comprising a plurality of disks, some of which are fixedly carried 25 and others rotatably carried by the spindle, the disks provided with peripheral notches therein, means co-acting between adjacent disks whereby the disks may be selectively rotated and the peripheral notches brought 30 into alignment, a notched locking bar secured in the frame and disposed parallel to the spindle, the disks adapted to project into the notch in the locking bar when the spindle is at one end of its stroke, and the locking bar 35 adapted to project into the aligned peripheral notches in the disks as the spindle is moved to the opposite end of its stroke, and 40 stops carried by the spindle and co-acting with the frame for positively locking the spindle against sliding motion at either end of its stroke as desired.

45. 9. A combination lock comprising a frame, a spindle slidably and rotatably mounted therein, a disk assembly carried by the spindle, said assembly comprising a plurality of disks some of which are fixedly

carried and others rotatably carried by the spindle, means co-acting between adjacent disks whereby the rotatably mounted disks may be selectively rotated when the spindle 50 is at one extreme end of its stroke, an inclined spring plate mounted in the frame and engaging the peripheral edges of the disks, locking means co-acting with the disks and normally preventing sliding of the spindle 55 and disks from the aforesaid end position, means for releasing said locking means and permitting sliding of the spindle when the disks have been rotated to a predetermined relative angular 60 disposition to each other and to the spindle, and means for preventing rotation of the disks and spindle when the spindle is at the opposite end of its stroke.

10. A combination lock comprising, a frame, a spindle slidably and rotatably 65 mounted therein, a disk assembly carried by the spindle, said assembly comprising a plurality of disks some of which are fixedly carried and others rotatably carried by the spindle, the rotatably carried disks being of 70 greater diameter than the fixedly carried disks, means co-acting between adjacent disks whereby the rotatably mounted disks may be selectively rotated, when the spindle 75 is at one extreme end of its stroke, an inclined spring plate mounted in the frame and engaging the peripheral edges of the rotatably carried disks, locking means co-acting with the disks and normally preventing 80 sliding of the spindle and disks from the aforesaid end position, means for releasing said locking means and permitting sliding of the spindle when the disks have been rotated to a predetermined relative angular 85 disposition to each other and to the spindle, and means for preventing rotation of the disks and spindle when the spindle is at the opposite end of its stroke.
